(57) **CLAIM**

The ornamental design for a welding helmet as shown and described.

DESCRIPTION

FIG. 1 is a perspective view of our new design for a welding helmet;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings depict portions of the welding helmet that form no part of the claimed design, and the shading is provided to illustrate contour only and is not an indication of texture, gloss, etc.
